UNITED STATES PATENT OFFICE.

JAMES INGELS, OF SPRINGFIELD, ILLINOIS.

INSULATOR FOR SPARK-PLUGS.

1,341,747.

Specification of Letters Patent. Patented June 1, 1920.

Application filed November 28, 1919. Serial No. 341,081.

To all whom it may concern:

Be it known that I, JAMES INGELS, a citizen of the United States, residing at Springfield, in the county of Sangamon and State of Illinois, have invented a new and useful Insulator for Spark-Plugs, of which the following is a specification.

This invention relates to insulators, commonly of porcelain, mica or glass, such as are used in conjunction with the spark plugs of internal combustion engines.

The purposes of the invention are: to provide an insulator of new and improved form adapted to utilize more effectively than has hitherto been done the heat absorbed by and radiated from the insulator during the operation of the engine with which the spark plug is used; to provide an insulator having a combustion chamber wholly within the insulator in contradistinction to insulators of the type in which the space between the outer surface of the insulator and the inner surface of the casing of the spark plug is the combustion chamber; to provide an insulator formed to fit closely in the casing of the spark plug in order that the wall of the casing may reinforce and strengthen that wall of the insulator which surrounds the combustion chamber, thus minimizing the risk of rupture of the insulator by the force of the explosions in the engine cylinder; to provide in the body of the insulator a pocket entirely apart from the combustion chamber adapted to house means for adjusting the electrode; and to provide other new and useful structural details.

The invention is illustrated in the annexed drawing, to which reference is hereby made and will now be described and the novel features thereof will be recited in the claims.

Figure 1 is a combined view showing in elevation an insulator embodying my invention and showing in vertical section the casing and the bushing of a spark plug in which the insulator is installed; Fig. 2 is a vertical longitudinal section through the insulator on the line 2. 2. of Fig. 1; Fig. 3 is a horizontal transverse section through the insulator and the casing of the spark plug on the line 3. 3. of Fig. 1; and Fig. 4 is a horizontal transverse section through the insulator and the casing of the spark plug on the line 4. 4. of Fig. 1. The same reference numerals designate the same parts

in all the views. In the drawings only so much of the casing and bushing of the spark plug is shown as is necessary to show the relation of those parts to the insulator.

Spark plug casings and bushings of various forms are made and used. I have shown in the drawings a well known type of spark plug and an insulator fitted to that particular type of spark plug. It is to be understood however, that my invention is not restricted to an insulator of the precise form shown, since it is obvious that the external contour of the insulator may be varied to suit the internal contours of the casings and bushings of different spark plugs without changing any essential internal construction of the insulator.

The insulator will be made of porcelain, mica, glass or other material most suitable for the particular purpose for which the insulator is to be used.

The insulator of preferred construction comprises a circular body 5, a circular upper member 6, of less diameter than the body 5, a circular lower member 7, of less diameter than the body, a beveled shoulder 8 at the juncture of the member 6 with the body 5, a shoulder 9 at the juncture of the member 7 with the body 5, a central bore 10 extending through the member 6, the body 5 and the member 7. Inside the member 7 is a circular combustion chamber 12, the height of the chamber being approximately equal to the diameter of the member 7. Inside the chamber 12 is a sleeve 13 integral with the member 7. The wall of the sleeve 13 protects the electrode 14 and is practically the same thickness as the circular wall of the combustion chamber in order that both may be heated alike during the compression and explosion of gases in the combustion chamber and may alike radiate heat to effectually volatilize any hydrocarbon remaining in the combustion chamber after any explosion, so that at the next succeeding ignition the accumulated hydrocarbon will be burned and the interior of the combustion chamber will thereby be completely cleaned and will continue to be self-cleaning so long as the engine remains in operation.

Inside the body 5 is a pocket 15 adapted to house an adjusting nut 16 and keep it from turning. After the nut is in place in the pocket supplemental insulation 17 will be used to close the mouth of the pocket.

105

110

The spark plug casing 18 and the bushing 19 are commonly of brass. The bushing screws into the casing.

In the present instance the circular outer wall of the member 6 contacts closely with the inner wall 20 of the bushing 19, the circular outer wall of the body 5 contacts closely with the inner wall 21 of the casing 18; the circular outer wall of the member 10 7 contacts closely with the inner wall 22 of the screw member 23 of the casing 18; a copper-asbestos gasket 24 is interposed between the shoulder 8 of the insulator and the flared terminal 25 of the bushing; and 15 a similar gasket 26 is interposed between the shoulder 9 of the insulator and the flared terminal 27 of the member 23 of the casing. By reason of the continuous close contact of practically the entire outer surface of the 20 insulator with the inner surfaces of the casing and the bushing the insulator is reinforced and strengthened to withstand the hard service to which it is subject.

The electrode 14 is screw threaded for 25 the greater part of its length and screws into the stationary nut 16. Upon rotating the electrode its lower terminal may be moved inward or outward according to the

direction, to vary the spark gap as may be desired.

Having fully described my invention, what I claim as new and desire to secure by Letters Patent is:

1. An insulator comprising a body; an annular terminal member; a central member within the annular terminal member; a pocket adapted to hold a stationary electrode-adjusting device; and a central bore extending through said body and through said central member. 35

2. A main insulator comprising a body having a central bore extending practically the entire length of the insulator; a combustion chamber wholly within the insulator; and a pocket adapted to hold a non-rotative electrode-adjusting device; in combination with a supplemental insulator closing the mouth of the pocket of the main insulator. 40

In witness whereof I have hereunto signed my name at Springfield, Illinois, this 24th day of November, A. D. 1919.

JAMES INGELS.
